BALL PEN

Walter Scholz, Stuttgart, Germany

Application June 16, 1951, Serial No. 231,927
In Germany March 27, 1950

1 Claim. (Cl. 120—42.4)

1

This invention relates to a ball pen.

The so-called ball pens use as a writing element a ball which is held in the cone-shaped front or writing end of the pen holder. The ball is usually held in its place in the writing end by a beaded edge and must for this purpose be covered to about two thirds. This makes it impossible to write with the pen in the usual angular writing position. One object of my invention is to overcome this disadvantage and to make it possible to use a ball pen in the same manner as other pens are used when writing.

Another disadvantage of the known ball pens is that they are not suitable for use with ink of high fluidity because such ink would easily flow out and would also tend to obstruct the narrow channels by forming a crust when in contact with air. Viscous paste inks have, therefore, been developed for the use in ball pens but these special inks are apt to undergo changes under the influence of changing temperature. Thus, a further object of my invention is to provide a ball pen which can be used with ink of high fluidity.

Ball pens have become known in which the writing ball is held by a magnet inserted in the front end of the pen holder. While the ball in these pens can be arranged to protrude halfway from the end of the holder, thus making writing in an angular position possible, other shortcomings, however, have not been overcome in the design of those ball pens.

To the accomplishment of the foregoing and other objects which will hereinafter appear, my invention consists in the ball pen elements and their relation one to the other, as hereinafter are more particularly described in the specification and sought to be defined in the claims. The specification is accompanied by a drawing in which:

Fig. 1 is a partially sectioned elevation of the front end of a ball pen when not in use, the pen embodying features of my invention;

Fig. 2 is a similar view, but showing the pen in writing position;

Fig. 3 is a partially sectioned elevation of a detail; and

Figs. 4 to 6 are an elevation, plan view, and perspective view, respectively, of the same detail.

Referring to the drawing in greater detail, the ball 1 preferably made from stainless steel is supported in a spherical seat provided at the apex of a conical member 3. The radius of the seat 2 is substantially the same as that of the ball 1 so as to ensure a large contact area between the

2

seat and the ball. The member 3 fits in a hollow space of the front end part or portion 4 of the ball pen and is arranged to move therein axially within narrow limits provided, for instance, by three stops 5. The end portion 4 is provided with a hollow extension tube 6 the outer wall of which may be smooth or threaded. The extension 6 is received in the hollow holder body 7 which confines the ink well.

Arranged within the member 3 is a permanent magnet rod 8 which may be inserted, as is shown in Figs. 3 and 4, in the bore 9 of the member 3 and may be held therein by means of the threaded plug 10 which protects the magnet 8 from coming in contact with the ink. The bore 9 does not extend to the seat 2 so that the ball 1 is only in contact with the non-magnetic material of the member 3. The distance of the front face of the magnet 8 from the ball seat 2 must, of course, be such that the magnetic field will be sufficiently strong to prevent the ball from falling out. On the other hand, the magnetic field must be sufficiently weak so as not to interfere with the rotation of the ball during writing. The member 3 is preferably made from plastic material.

Since the member 3 and the pen end portion 4 fit each other accurately, the member 3 in its forward position (Fig. 1) will close the ink well 11 tightly. In the rearward position of the member 3, the rearward or upper position being controlled by the stops 5, an annular opening forms between the member 3 and the inner wall of the end portion 4 through which ink flows to the ball surface. The closing position of the member 3, as shown in Fig. 1, is automatically assumed when the pen holder is held with its pen point downwards. When writing, the member 3 is automatically moved, due to the writing pressure, to its upper position shown in Fig. 2, in which position ink is permitted to flow to the writing ball. When the pen is held with the point upwards, the member 3 will move against the stops 5 and will open the annular passage, but in this position no ink will flow out.

The conical surface of the member 3 is preferably provided with ink grooves 12 which commence at the annular surface engaging the stops 5 (see Fig. 6) and run lengthwise, but which do not extend to the ball seat so as not to interfere with the obstruction to the passage of ink in the idle position of Fig. 1. Aside from the ink grooves 12, there are channels 13 provided in the member 3, which channels commence at the same annular rear face and are arranged and dimensioned so as to permit the passage of the stops 5. In a

certain rotational position it is, therefore, possible to move the member 3 past the stops 5 and to remove it for cleaning, repair or replacement purposes.

The end portion 4 of my pen holder surrounds 5 approximately one half of the ball 1 so that the ball in its writing position protrudes sufficiently far out to permit writing under the usual oblique pen angle.

At the highest point of the seat 2 there may be 10 a small aperture 14 in the member 3 to serve as, a receptacle for a small quantity of a lubricant. The lubricant facilitates the movement of the ball without interfering with the flow of the ink on the surface of the ball and also protects a 15 ball made of ordinary steel from rusting.

The body 7 may be designed like the body of a fountain pen. It may, for example, be provided with a piston type suction device. Thus, it is possible to use for my ball pen the same body as 20 for a fountain pen. When the pen is to be filled by suction, the ball end is submersed in ink. Due to the suction condition, the member 3 is removed from its idle position (Fig. 1) to allow ink to fill the well 11. As soon as the suction subsides, the member 3 returns to its closing position. When it is desired to empty the pen, the ball is held against a solid surface to move the member 3 into the writing position of Fig. 2, and to permit the ink to be removed by pressure 30 through the opening formed.

From the foregoing it will be clear that the ball pen of my invention has been greatly improved by setting the magnet in a conical member which is arranged to move in the front end portion of the pen holder, whereby the movement of said member is limited by stops, and the member controls the flow of writing fluid to the ball. When not in use, the conical member shuts off 35 the flow of writing fluid when the pen points 40

downwardly so that no fluid can escape. Under writing pressure, the conical member moves slightly inwardly and opens a passage for the writing fluid. It is, thus, possible to use ink of high fluidity as the writing fluid. Due to the ball being held by a magnet, it may be arranged so as to protrude at least halfway from the front end of the pen holder and, therefore, not interfere with writing with the pen being held in an oblique position.

I claim:

Ball pen comprising a main body, a front end part, a conical member arranged to slide axially within said part, stops projecting from the inner wall of the front end part and limiting the inwardly directed movement of said member, a magnet disposed within the conical member, a ball seated at the apex of the conical member and held in abutting relationship to said member by the magnet, said member being provided at its outer surface both with grooves and channels to conduct ink, which grooves and channels extend lengthwise but do not extend to the ball seat, said channels allowing said stops to pass, and allowing the conical member to be inserted and removed.

WALTER SCHOLZ.
